UNITED STATES PATENT OFFICE

129,792

DESIGN FOR A DRESS

Helga Oppenheimer, Little Neck, Long Island,
N. Y.

Application September 13, 1941, Serial No. 103,329

Term of patent 3½ years

To all whom it may concern:

Be it known that I, Helga Oppenheimer, a citizen of the United States, residing in Little Neck, Long Island, in the county of Queens and State of New York, have invented a new, original, and ornamental Design for a Dress, of which the following is a specification, reference being had to the accompanying drawing, forming part thereof.

I claim:

The ornamental design for a dress, substantially as shown.

HELGA OPPENHEIMER.
